UNITED STATES PATENT OFFICE.

DELOSS BORLAND, OF CHARLESTON, MISSISSIPPI.

COMBINED LOCK AND LATCH.

1,143,492.

Specification of Letters Patent. Patented June 15, 1915.

Application filed November 13, 1914. Serial No. 871,953.

To all whom it may concern:

Be it known that I, DELOSS BORLAND, a citizen of the United States of America, residing at Charleston, in the county of Tallahatchie and State of Mississippi, have invented new and useful Improvements in Combined Locks and Latches, of which the following is a specification.

This invention relates to certain novel and useful improvements in combined locks and latches.

In carrying out the present invention, it is my purpose to provide a device of the class described wherein the latching bolt operated by the knob spindle may be latched in projected position from the inside of the door so that movement of the latching bolt under the action of the knob spindle from the outside of the door will be prevented.

It is also my purpose to provide means for holding the latching bolt in projected position, which will be operable from the inside of the door and preferably carried by the escutcheon plate.

A further object of my invention is to provide means of the class described which will embrace the desired features of simplicity, efficiency and durability, which may be applied to any type of door lock now in use and which may be put into and out of service quickly and conveniently.

With the above and other objects in view, the invention consists in the construction, combination and arrangement of parts hereinafter set forth in and falling within the scope of the claim.

In the accompanying drawings; Figure 1 is a fragmentary side elevation of the inner side of a door having the lock thereof equipped with means constructed in accordance with the present invention. Fig. 2 is a vertical sectional view therethrough. Fig. 3 is a horizontal sectional view through the same. Fig. 4 is a perspective view of the device removed from the escutcheon plate. Fig. 5 is a view similar to Fig. 1 showing a modified form of the invention, parts being broken away to show the mechanism within the lock casing. Fig. 6 is a vertical sectional view on the line 6—6 of Fig. 5. Fig. 7 is a face view of the escutcheon plate removed from the door. Fig. 8 is a view in side elevation of the latching bolt removed from the casing.

Referring now to the drawings in detail, 1 designates a portion of the door at the

forward edge thereof, such portion being formed with a mortise 2 opening onto the forward edge and seated within the mortise 2 is an appropriate form of combined lock and latch 3 embodying the usual locking bolt 4 capable of sliding movement to projected and retracted positions under the action of a key, and a latching bolt 5 adapted for sliding movement to projected and retracted positions, the outer ends of the bolts 4 and 5 being movable into openings formed in the door jamb, as usual.

Suitably fastened to the inner and outer surfaces of the door are escutcheon plates 6 respectively formed, adjacent to the upper ends thereof, with openings 7 alining with openings 8 in the casing of the lock 3 and passed through these alining openings and the operating device of the latching bolt 5 is a knob spindle 9 having the inner and outer ends thereof provided with the usual knobs 10. Also formed in the escutcheon plates 6 below the openings 7 therein are key holes 11 alining with each other and with similar holes formed in the lock casing so that a key may be introduced in the lock to actuate the locking bolt 5.

In accordance with my present invention, the side wall of the casing of the combined lock and latch 3 adjacent to the inner side of the door is formed with a vertical slot 12 disposed immediately behind the latching bolt 5 and formed in the adjacent wall of the mortise 2 is a similar slot 13 registering with the slot 12. Through these slots is passed a latching pin 14 having one end thereof terminating within the lock casing and the outer end connected with a depending arm 15 disposed immediately adjacent to and parallel with the inner face of the escutcheon plate 6 on the inner side of the door. Formed in the last-mentioned escutcheon plate adjacent to the lower end of the arm 15 is a vertical slot 16 and passed through the slot 16 is a pin 17 having the inner end thereof secured within an opening in the lower extremity of the arm 15, and the outer end provided with a thumb piece 18. In the present instance, a leaf spring 19 surrounds the pin 17 between the confronting faces of the escutcheon plate and arm 15 and acts to hold the thumb piece 18 in frictional engagement with the exposed surface of the escutcheon plate, so that the thumb piece will be held in actuated position.

In practice, when it is desired to hold the

latching bolt 5 against movement to retracted position under the action of the knob spindle 9 and knob 10, so that opening of the door from the outer side thereof will be prevented, the pin 17 is moved upwardly within the slot 16 under the action of the thumb piece 18, thereby sliding the arm 15 in a similar direction to elevate the latching pin 14 and in this movement of the latching pin 14, such pin is disposed immediately behind and in the path of movement of the latching bolt so that inward movement of such bolt is prevented under the action of the knob spindle. To relieve the latching bolt 15 of the influence of the latching pin 14 the pin 17 is moved toward the lower end of the slot 16 under the action of the thumb piece 18, thereby withdrawing the latching pin from the path of movement of the latching bolt, the leaf spring 19 holding the latching pin in elevated and lowered positions.

In the modified form of the invention illustrated in Figs. 5 to 8 inclusive, the lower edge of the latching bolt 5 adjacent to the rear end thereof is formed with a depending lug 20 and the inner end of the latching pin 14 is disposed adjacent to the lug 20 and capable of movement into the path of such lug, while the arm 15 carrying the pin 14 is disposed within a guide 21 suitably secured to the inner surface of the escutcheon plate. When the latching pin 14 is elevated and disposed in the path of movement of the lug 20 movement of the latching bolt 5 to retracted position under the action of the knob spindle is prevented, while when the latching pin is lowered to release the lug 20 the latching bolt may be retracted from the outer side of the door by rotating the knob spindle.

From the foregoing description taken in

connection with the accompany drawings, the construction, mode of operation and manner of employing my improved latching device for the latching bolts of combined locks and latches will be readily apparent.

It will be seen that I have provided a device whereby the latching bolt may be locked in projected position so as to prevent opening of the door from the exterior thereof, while the parts of the device are so correlated and arranged as to reduce the possibility of derangement to a minimum.

I claim:

In combination, a combined lock and latch adapted to fit in the mortise in a door and escutcheon plates secured to the opposite sides of the door, one side wall of the casing of said lock having a slot formed therein, a pin extending through said slot and working therein and capable of movement to a position to hold the latching bolt against inward movement, an arm connected to one end of said pin and disposed immediately adjacent to and in parallelism with the escutcheon plate at the inner side of the door, said last-named plate having a vertical slot formed therein, a pin extending through said last slot and connected with the adjacent end of said arm, a thumb piece on the outer end of said pin whereby said arm may be actuated to operate said first-named pin, and a leaf spring interposed between said arm and the adjacent face of the escutcheon plate to hold the arm in operated position.

In testimony whereof I affix my signature in presence of two witnesses.

DELOSS BORLAND.
